UNITED STATES PATENT OFFICE

2,589,531

PAINT LOOSENING AND SCRAPING DEVICE

Vern E. Brooks, Fort Worth, Tex.

Application August 1, 1949, Serial No. 107,905

4 Claims. (Cl. 15—23)

1

The present invention relates to certain new and useful improvements in manually usable improvements and devices employable by painters and others for loosening and scraping paint, as a step preparatory to repainting the thus conditioned surface.

More specifically, the invention has to do with a simple and easily usable device which takes the form of a so-called screen pad and which functions effectively in removing paint blisters, scales and corrosion from outside painted surfaces on houses, barns, fences, tanks and which, in addition, is satisfactorily employable to remove rust scales from pipes, farm implements and the like.

In carrying out the principles of the invention I provide a novel arrangement of two or more sheets or pieces of screen wire and assemble these on a handle-equipped base or form so that the two pieces are in superimposed relationship and so that, when in use, they rub frictionally against each other to sear and cut blisters and hanging paint and are substantially self-cleaning.

In reducing to practice the preferred embodiment of the invention I have provided a reliable and inexpensive screen pad which is sufficiently durable that it does not tear easily on wood splinters, nail heads or other contacted objects. It is sufficiently self-cleaning in action that it does not clog with old paint and dirt while in use and is superior to steel bristled brushes and similar scrapers in that it does not scratch and mutilate wood surfaces.

Briefly, I attain the wanted ends through the instrumentality of a sheet metal form which is bent to provide a receiver and retainer for a handle-forming block, which provides a backing plate for the plurality of plies of screen wire and also serves to anchor the edge portions of the wire while, at the same time, allows said plies of wire to be replaced when unduly worn.

Other objectives will be clear from the succeeding description and the accompanying illustrative drawings.

In the drawings, wherein like numerals are employed to designate like parts throughout the views:

Figure 1 is a perspective view of a manually usable paint loosening and scraping device constructed in accordance with the principles of the present invention;

Figure 2 is a central cross-section taken approximately on the plane of the line 2—2 of Figure 1, looking in the direction of the arrows;

Figure 3 is a plan view, on a small scale, of the 55 solid backing for the main stretches of the screens

2

sheet metal blank from which the receiver-form is constructed; and

Figure 4 is a plan view of one of the sheets of screen wire.

Referring now to the drawings by reference numerals and lead lines it will be seen that the several main parts comprise a wooden or equivalent block 6, a receiver and holder 7 therefor and two plies of screen wire, one of which is shown 10 in Figure 4 and denoted by the numeral 8.

Reference being had to Figure 3 which shows the blank of metal, this is stamped out to provide a main rectangular plate or body portion 9 which is essentially a backing plate for the 15 screen wire means. The marginal edge portions have two outstanding longitudinal main flanges 11 and 12 and the transverse end portions have outstanding narrower main flanges 13 and 14. These flanges are defined by the fold lines 15 and 16, respectively. Flanges 11 and 12 have additional fold lines 17—17 and these, in turn, define auxiliary flanges 18—18. The end flanges 13 and 14 have fold lines 19—19 defining auxiliary flanges 20—20. Flanges 11, 12, 13 and 14 are bent up at right angles to the main body plate 9 and thus define a pan-like receptacle. This receptacle serves as a receiver and holder for the wooden block 6 and the block is fastened therein by punching the metal and embedding the indentations, as at 10, into the wood. The remaining flanges 18 and 20 are down-bent on the fold lines 17 and 19 and these serve as adapters and retainers for the upbent edge portions 21 and 22 of the inner and outer screens 23 and 24 the 25 adjacent transverse ends of the flanges 18 and 20 are spaced an appreciable distance apart to provide clearance spaces. In Figure 4, I have shown a plan view of the inner screen or blank 23 with its bendable retaining flanges 22. In practice the 30 screens are superimposed upon each other and are backed up and stretched and held in position by the form or base plate 9. The flanges 21 and 22 of the respective screens are then bent up at right angles as shown in Figure 2 and are retained by down-bent flanges 18—18 and 20—20 (Figure 35 1). The tension of the screen wire when thus bent and assembled in said flanges holds itself in place without the need of additional clamps or bands.

It will be seen that the sheet metal unit 7 is, therefore, bent up into pan-like form and constitutes a receiver and holder for the wooden block and the wooden block, in turn, serves as a handle. The plate portion 9 also serves as a 40 solid backing for the main stretches of the screens

23 and 24. The exterior downbent flanges 18-18 and 20-20 serve as retainers for the bent edges or flanges 21 and 22 of the respective screens. It follows that I, therefore, produce a novel so-called screen pad mounted on a sheet metal back-
ing or form, said form carrying a wooden block serving as a handle.

Since the two screens are resilient and relatively loose in respect to each other and also in respect to the backing plate 9 they are allowed to shift and rub against each other with the result that common sheets or pieces of screen wire (14 x 18) mesh produce the desired frictional, cutting and surface cleaning requirements. More importantly, however, the rubbing of screen 15 against screen achieves the aforementioned shearing of the cuttings which would otherwise lodge between the screens and reduces clogging of the meshes to a minimum.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A manually usable paint and scale loosening and scraping device comprising a substantially rectangular flat rigid backing plate having upstanding longitudinal and transverse flanges, the upper edges of said flanges being provided with return bends carrying downwardly directed screen wire accommodating and retaining flanges, the latter being narrower than said first named flanges and having edge portions terminating on a plane above said backing plate, substantially duplicate sheets of screen wire superimposed one on the other and having upwardly directed longitudinal and transverse marginal flanges contacting said first named flanges and frictionally clamped against said first named flanges by said second named flanges, said sheets being relatively loose in respect to each other and also in respect to the backing plate and having their coating meshes in relatively shiftable rubbing contact to shear and reduce adhering cuttings and to free the latter from said meshes to render the screens virtually self-cleaning, and handle means for said backing plate.

2. The structure specified in claim 1, wherein said handle means is in the form of a block with its horizontal bottom surface in contact with the entire upper surface of the backing plate and its marginal vertical surfaces in contact with said first named flanges, the upper portion of said block projecting above said first named flanges and providing a hand grip.

3. The structure specified in claim 2, wherein said longitudinal flanges are each provided with a centrally positioned inwardly projecting detent engaging coating surfaces of said block to retain the same in its operative position.

4. A manually usable paint and scale loosening and scraping device comprising a substantially rectangular flat rigid backing plate having upstanding longitudinal and transverse flanges, said longitudinal flanges each having a centrally positioned inwardly projecting detent, the upper edges of said flanges being provided with return bends carrying downwardly directed screen wire accommodating and retaining flanges and having edge portions terminating on a plane above said backing plate, the adjacent transverse ends of said second-named flanges being spaced appreciable distances apart to provide unobstructed clearance spaces, substantially duplicate sheets of screen wire superimposed one on the other and each having upwardly directed longitudinal and transverse marginal flanges contacting said first-named flanges on said backing plate and frictionally clamped against said first-named flanges on the backing plate by said second-named flanges on said backing plate, said sheets being relatively loose in respect to each other and also in respect to the backing plate and having their coating meshes in relatively shiftable rubbing contact to shear and reduce adhering cuttings and to free the latter from said meshes to render the screens virtually self-cleaning, and a block with its horizontal bottom surface in contact with the entire upper surface of said backing plate and its marginal vertical surfaces in contact with said first-named flanges on said backing plate, the upper portion of said block projecting above said first-named flanges providing a hand grip, each detent on said longitudinal flanges being in operative engagement with the coating surfaces of said block.
